UNITED STATES PATENT OFFICE.

JAMES WILKINSON, OF BOSTON, MASSACHUSETTS, ASSIGNOR TO GENERAL ELECTRIC COMPANY, A CORPORATION OF NEW YORK.

COMBINATION FLUID-FLOW METER.

1,121,961.

Specification of Letters Patent. Patented Dec. 22, 1914.

Application filed October 9, 1912. Serial No. 724,736.

To all whom it may concern:

Be it known that I, JAMES WILKINSON, a citizen of the United States, residing at Boston, county of Suffolk, State of Massachusetts, have invented certain new and useful Improvements in Combination Fluid-Flow Meters, of which the following is a specification.

This invention relates to meters for indicating the flow of fluid through a conduit, and its object is to provide an instrument which shows in parallel columns the quantity of water supplied hourly to a steam boiler, and the quantity of steam generated hourly by said boiler. The advantage of having these two facts displayed in proximity is, that the fireman can see at a single glance whether the water is being fed at too high or too low a rate and whether the boiler is making too much or too little steam, and can regulate the water and the fire accordingly. In a boiler room containing a battery of boilers the meters will all be located on the same level, so that they can all be read and compared from either end of the room and the fires can be properly handled to keep the input of water and the output of steam as nearly uniform as possible for all the boilers.

In the accompanying drawings, Figure 1 is a side elevation of one of my combination meters; Fig. 2 is a front view of the same; Fig. 3 is an end view of a boiler provided with such a meter; and Fig. 4 is a diagrammatic view showing in perspective a battery of five boilers so equipped.

A bracket 1 projects from the front of the boiler and supports side by side two U-tubes or their equivalent, in which are masses of mercury or the like whose level in the legs of said tubes can be varied by fluid pressure. The tubes are contained in a casing 2 which has glazed openings 3 3' in its sides so that the level of the mercury 4 or its equivalent can be read by means of suitable graduation marks 5 on the walls of the casing adjacent to said openings.

The spaces above the mercury in the two legs of one tube are connected by pipes 6 with the leading and trailing faces of a pressure difference device, such as a nozzle plug 7 inserted in the feed water pipe 8 of the boiler and responding to changes in the velocity of flow of the water. The other tube is similarly connected by pipes 9 with

a nozzle plug 10 in the steam pipe 11 of the boiler. The varying water flow in pounds per hour will therefore be indicated by the variations of the column of mercury visible through the opening 3 while the column in front of the opening 3' will indicate the variations in steam flow in pounds per hour.

When a battery of boilers discharging into a common main or system of piping is equipped with these meters, a person standing at either end of the boiler room can look down the entire row and see just how each boiler is behaving in relation to the others, and what proportion of their common load it is carrying. Thus in Fig. 4, the water feed rate for boiler 12 is too high and should be reduced, because its steam flow is all right. Boiler 13 shows correct conditions for both water and steam. The water feed for boiler 14 is all right, but the rate of steaming is too low, probably owing to a low fire, which calls for attention from the fireman. Boiler 15 is doing all right. At boiler 16, the water feed rate is too low, which has raised the rate of steaming too high, requiring more water, or a lowering of the fire, or both. The combination flow meter is therefore a valuable instrument for enabling the firemen to keep their boilers in a condition of highest efficiency.

In accordance with the provisions of the patent statutes, I have described the principle of operation of my invention, together with the apparatus which I now consider to represent the best embodiment thereof, but I desire to have it understood that the apparatus shown is only illustrative and that the invention can be carried out by other means.

What I claim as new and desire to secure by Letters Patent of the United States, is:

1. The combination with a steam boiler, of a combination meter therefor, comprising a casing having openings therein, two U-tube manometers associated with the casing, the indicating legs of which are visible through said openings, a flow responsive device in the feed water pipe, a flow responsive device in the steam main of the boiler, and pipes connecting each of the flow responsive devices to a corresponding manometer.

2. The combination with a battery of boilers, of a combination meter for each boiler, comprising a casing having openings in its sides, two U-shaped mercury columns in said casing whose variations in level are visible

through said openings, and flow-responsive devices in the feed water pipe and steam main of said boiler connected respectively with said two columns.

- 5 3. The combination with a boiler, of a main discharging vapor therefrom, a conduit supplying liquid thereto, a meter containing two adjacent receptacles, both containing fluid, a means associated with the 10 main and responsive to variations in the rate of flow of vapor from the boiler to cause

movement of the fluid in one receptacle, and a second means associated with the conduit and responsive to variations in the rate of flow of liquid to the boiler to cause movement of the fluid in the other receptacle. 15

In witness whereof I have hereunto set my hand this 8th day of October, 1912.

JAMES WILKINSON.
